UNITED STATES PATENT OFFICE.

LOUIS KALVIN, OF NEW YORK, N. Y.

EYE MECHANISM FOR DOLLS.

1,275,698.

Specification of Letters Patent. Patented Aug. 13, 1918.

Application filed May 25, 1918. Serial No. 236,492.

To all whom it may concern:

Be it known that I, LOUIS KALVIN, a citizen of the United States, residing in New York, in the county and State of New York, 5 have invented certain new and useful Improvements in Eye Mechanism for Dolls, of which the following is a full and clear specification.

The present invention relates to improvements in eye mechanism for the so-called "sleeping dolls", and the object of the invention is to simplify and improve such mechanism, with a view to facilitating the mounting and de-mounting of the mechanism in 10 the doll head and the automatic adjustment of the eyes and lids, with reference to the eye sockets of the head, not only when mounting the mechanism in the head, but in cases of shrinkage of the material of the 15 head after the completion of the manufacture.

To this end I have devised the doll head eye mechanism, comprising an eye supporting plate or frame having means adapted to 20 engage the inner surface of the hollow doll head at a plurality of points and having a detachable locking device arranged to secure the plate in proper position, with reference to the eye sockets of the head. The means 25 of engagement of the supporting plate with the head are preferably the lower fixed lid members and one or more adjustable detents formed of pointed screws threaded through the plate and engaging the inner surface of 30 the hollow head. By adjusting the pointed screws the angular relation of the plate to the head, with especial reference to the eye 35 sockets can be fixed to a nicety. The locking member consists preferably of a spring 40 member engaging the inner surface of the head and the locking plate for holding it securely in place.

The eye supporting plate is preferably formed with slots to receive tongues projecting 45 from socket members, to which the eye members are attached. The socket members are preferably provided with lower lid members of spheroidal segmental shape with outwardly presented flanges adapted to accurately engage the lower edges of the eye 50 sockets of the head. The tongues of the eye attaching socket members loosely engage the slots of the supporting plate, so as to be

movable thereon to adjust themselves automatically upon the supporting plate to retain proper relation with the eye sockets. 55

The upper movable lids are pivoted to the supporting frame upon a rod and are adjustably secured together by means of inwardly presented tongues that are bent into oval or other non-circular shape, so as to telescope one within the other, keying the two lid members together and permitting their relative lateral adjustment. The counter balance for the movable lids is suitably attached to a tongue projecting from one of the lid members. 60

In order that my invention may be fully understood it will first be described with reference to the accompanying drawings and 70 afterward pointed out more particularly in the annexed claims.

Figure 1 is a vertical sectional view of a doll's head, showing my improved eye mechanism applied thereto; 75

Fig. 2 is a front view of the eye mechanism upon its supporting plate, removed from the head;

Fig. 3 is a vertical sectional view taken on the line 3—3 of Fig. 2; 80

Fig. 4 is a face view of the supporting plate of the eye mechanism;

Fig. 5 is a detail front view of the lower lid and eye supporting socket;

Fig. 6 is a detail sectional view showing 85 the eye member secured in the supporting socket;

Fig. 7 is a detail sectional view showing the adjustable connection between the movable eyelids; 90

Fig. 8 is a sectional view of the doll's head of the closed crown type, showing a slight modification of the spring locking device.

1 is a hollow doll's head formed as usual 95 with the eye sockets, 2, and the open crown 3.

5 is an oblong stamped sheet metal plate, formed with a strengthening rib or bead 5^a around its edges and with two oppositely 100 arranged oblong slots 6, to receive the eye and lower lid members presently to be explained. Plate 5 is also formed with a central opening 7, through which projects the counter balance of the upper lid mechanism, 105 and screw threaded sockets 8 to receive the

adjustable pointed screws that assist in determining the location of the supporting plate in the doll head.

10 is a shallow sheet metal cup formed with an annular convex rim 11 and with a segmental spheroidal wall 12, having a curved lower lid flange 13. The bottom wall of cup member 10 is perforated to form two integral attaching tongues 14, which are adapted to pass through one of the slots 6 in plate 5 and be bent over against the under face of the plate to secure socket member 10 in position, but movable freely in the slot 6 upon the plate 5, for the purpose of affording automatic adjustment as herein-after explained.

15 is the eye member, formed of a hollow hemispherical shape of suitable material in the usual way. The eye member 15 fits snugly in the cup 10, within the annular flange 11 and segmental flange 12, and is engaged by a pin 16, carried by lug 17 upon flange 11. The pin 16 is designed to fit a proper perforation in the side wall of eye member 15.

The upper movable lid members consist of two separately formed spheroidal segments 20 and 21, having at their outer edges perforated lugs 20^a and 21^a and at their inner edges integral tongues 20^b and 21^b, which latter are bent or shaped into elliptical or other non-circular cross sectional form, as shown particularly in Fig. 7 and telescoped one within the other to adjustably key the two lid members together, so that they will rock in unison and can be adjusted with relation to each other upon their axis of motion. 25 is a pivot rod supported in suitable openings formed through the flanges of cup members 10 and the side walls of the eye members 15. The pivot rod 25 passes through perforated pivot lugs 20^a and 21^a and through the central telescoping portions 20^b and 21^b of the upper lid members, thereby supporting the coupled members for rocking motion.

One of the lid members 21 is formed with an integral rearwardly projecting tongue 21^c, having perforation 21^d to receive the bent end 30^a of the curved counterbalance rod 30, tongue 21^c being bent around the rod 30 to secure it to the coupled movable eyelid members. Rod 30 carries the counterbalance weight 31, which holds the movable eyelids open when the doll is held upright and causes the eyelids to close when the head is put in a reclining position, thereby simulating sleep.

Screwed into the sockets 8 of supporting plate 5 are the two pointed screws 35 formed with squared heads 36. These screws are adapted to engage the inner surface of the hollow head above the eye sockets at two points to support the plate 5 in conjunction with the engagement of the lower lid mem-

bers 13 in proper relation to the eye sockets. By adjusting the screws 35 the angle of plate 5 can be accurately determined to effect the most life-like appearance of the eye and lid members.

A suitable detachable locking member is employed for securing the plate 5 in position within the head. I prefer to employ a locking member in the form of a curved spring, as shown at 40, with suitably bent ends 41, 42, engaging respectively under an angular ledge 3^a of the head and the upper wall of supporting plate 5. The shape of this spring locking member is such that plate 5 will be pressed downwardly and forwardly in the head to hold it securely in place with the lower lids 13 engaging the eye sockets and the adjustable pointed screws 35 engaging the inner surface of the head above the eye sockets.

In Fig. 8 I have shown a slight modification of the invention, in which the eye mechanism is the same as above described, but in which the form of locking spring 45 is modified to permit its insertion through the open neck, so as to adapt the eye mechanism to the form of hollow doll's head having a closed crown, a form which is largely used in making dolls' heads with imitation hair.

In placing the eye mechanism in the hollow doll's head, the parts having been properly mounted on the supporting plate 5, as just described, the mechanism is placed in the doll's head with the lower eyelids 13 in engagement with the lower edges of the eye sockets 2 of the head, the upper and lower lids and eye members being adjusted upon the plate either inwardly or outwardly to cause them to register accurately with the eye sockets of the head. Holding the parts in this proper relation the adjustable pointed screws 35 are operated to adjust the angle of the plate 5 and the parts carried thereby. The locking member or spring 40 is then snapped into place in proper engagement with the inner surface of the hollow head in the upper edge of the supporting plate 5 to hold the parts as shown in Fig. 1 of the drawings. The angle of mechanism in the head can be more accurately adjusted, if desired, by operating the screws 35 after the mechanism is in place.

The improved eye mechanism for dolls' heads is of simple and economical construction. The mounting of the eyes and lids upon the frame permits these parts to be accurately adjusted with relation to the eye sockets of the head. The adjustment of the main parts upon the plate is, in a sense, automatic, in that they will properly adjust themselves in the eye sockets, moving transversely upon the plate 5 when the plate is secured in position.

This capacity for adjustment of the eye mechanism upon the supporting plate is a

feature of great importance, particularly when the mechanism is mounted in composition heads that shrink or contract with age. In such shrinkage the eye and lid members 5 will be caused, by their engagement with the eye sockets and with each other, to automatically move upon their supporting plate transversely of the head to permit the contraction of the material. Such automatic 10 adjustment thereby takes place without injury to the head or the mechanism.

I am not aware that it has ever been proposed to mount an eye mechanism in a hollow doll's head by detachable means nor by 15 spring locking means as above described, by means of which the parts are yieldingly and effectively held in place to avoid disarrangement by jars or contraction of the material of the head. The mechanism is 20 also of value from a manufacturing standpoint, since it is produced by die work and a simple assembling operation. The adjustable and removable features afford convenient and economic means for mounting and 25 for the removal when repairs become necessary.

I claim:

1. The combination with a hollow doll's head formed with eye sockets, of a removable eye-supporting plate, means supporting said plate within the head in proper relation to said eye sockets, and locking means detachably securing the plate in place.

2. The combination with a hollow doll's head formed with eye sockets, of a removable eye supporting plate, means supporting said plate within the head in proper relation to said eye sockets, and spring locking means detachably securing the plate in place.

3. The combination with a hollow doll's head formed with eye sockets, of an eye-supporting plate, devices upon said plate engaging the inner surface of the head to support the plate in proper relation to said eye 40 sockets, and locking means engaging said plate and the inner surface of the head for detachably securing the plate in place.

4. The combination with a hollow doll's head formed with eye sockets, of a removable eye supporting plate having means engaging the inner surface of the head to support the plate in proper relation to said eye sockets, and a removable spring locking member engaging said plate and the inner 55 surface of the head for detachably securing the plate in place.

5. The combination with a hollow doll's head formed with eye sockets, of an eye-supporting plate, carrying means for engaging the inner surface of the head at a plurality 60 of points to support the plate in proper relation to said eye sockets, and locking means detachably securing the plate in place.

6. The combination with a hollow doll's 65 head formed with eye sockets, of an eye-

supporting plate having a plurality of devices adapted to engage with the inner surface of the head and support said plate in proper relation to said eye sockets, and spring locking means engaging said plate 70 and the inner surface of the head for detachably securing the plate in place.

7. The combination with a hollow doll's head formed with eye sockets, of an eye-supporting plate, members adjustably mounted upon said plate engaging the inner surface of the head to hold the plate in proper relation to said eye sockets and spring locking means detachably securing 75 the plate in place.

8. The combination with a hollow doll's head formed with eye sockets, of a removable eye supporting plate, pointed screws adjustably mounted in said plate and engaging the inner surface of the head to hold the 80 plate in proper relation to said eye sockets, and spring locking means detachably securing the frame in place.

9. The combination with a hollow doll's head formed with eye sockets, of a supporting plate for eyes and eyelids removably mounted in the head in proper relation to said eye sockets, means adjustably securing the eyes to said plate, and a removable spring locking member detachably securing 90 the plate in place.

10. The combination of a hollow doll's head formed with eye sockets, of an eye-supporting plate or frame carrying lower lid members adapted to engage the lower 100 edges of said eye sockets, and a removable locking member for detachably securing the plate or frame in place.

11. The combination of a hollow doll's head, having eye sockets, with a plate carrying eyes and eyelids arranged within the head with eyelids seated upon the walls of the eye sockets, and yielding means securing the plate in position.

12. The combination of a hollow doll's head, having eye sockets, with a plate carrying eyes and eyelids arranged within the head with eyelids seated upon the walls of the eye sockets, yielding means securing the plate in position and adjustable means upon the plate engaging the head for determining the angular position of the plate in the head.

13. The combination of a hollow doll's head formed with eye sockets of an eye supporting plate or frame carrying lower lid members adapted to engage the lower edges of said eye sockets, detents upon said plate or frame engaging the inner surface of the head, and a removable locking member for 120 detachably securing the plate or frame in place.

14. The combination with a hollow doll's head having eye sockets, of an eye supporting plate suitably mounted within the head, 130

and eye members movably mounted upon said supporting plate and automatically adjustable thereon into proper relation with the eye sockets of the head by the act of 5 mounting the supporting plate in position.

15. The combination of a hollow doll's head, having eye sockets, with a plate carrying eyes and eyelids arranged within the head with eyelids seated upon the walls of 10 the eye sockets, said eyes and eyelids being movable upon the plate to effect their automatic adjustment by the act of mounting the plate in the head, and means securing the plate in position.
- 15 16. The combination with a hollow doll's head formed with eye sockets, of a slotted supporting plate removably mounted within the head, eye attaching members adjustably engaging the slots of said plate and detachable means for locking the plate in position within the head.

17. The combination of a hollow doll's head formed with eye sockets, of a slotted supporting plate removably mounted within 25 the head, socket members formed with integral tongues engaging said slotted plate, and eye members mounted in said socket members.

18. The combination with a hollow doll's 30 head having eye sockets, cup shaped members formed with segmental lower lid members adapted to engage the eye sockets of the head, the eye members, means for securing the eye members in said cup-shaped 35 members, a slotted supporting plate, tongues projecting from said cup-shaped members and engaging the slots in said supporting plate, and means for detachably securing

the supporting plate in position within the head.

19. The combination with a hollow doll's 40 head, having eye sockets, of an eye supporting frame removably mounted within the head in proper relation to said eye sockets, a removable locking member engaging said frame and the inner surface of the head for detachably securing the frame in place, lower lid and eye members movably mounted upon said frame and adjustable thereon in relation to the eye sockets, and movable 45 upper lid members pivotally mounted upon said frame and adjustable toward and away from each other.

20. The combination with a hollow doll's 50 head, formed with eye sockets, of a supporting frame removably mounted in the head in proper relation to said eye sockets, lower lid and eye members secured together and movably mounted upon said frame and upper lid members pivotally mounted upon 55 said frame and formed with inwardly projecting tongues which are adjustably interlocked.

21. The combination with a hollow doll's 60 head, formed with eye sockets, of a supporting frame removably mounted in the head in proper relation to said eye sockets, lower lid members engaging the eye sockets, eye members mounted upon the lower lid members, means adjustably mounting said 65 lower lid members upon said frame, and upper lid members pivotally mounted upon the frame and adjustable relatively to each other.

LOUIS KALVIN.
